UNITED STATES PATENT OFFICE.

LOUIS A. SUEKOFF, OF CHICAGO, ILLINOIS.

UPHOLSTERING SPRING STRUCTURE.

1,167,856.

Specification of Letters Patent.

Patented Jan. 11, 1916.

Application filed January 11, 1915. Serial No. 1,525.

To all whom it may concern:

Be it known that I, LOUIS A. SUEKOFF, a citizen of the United States, residing at Chicago, in the county of Cook and State of Illinois, have invented certain new and useful Improvements in Upholstering Spring Structures, of which the following is a specification.

My invention relates to improvements in upholstering spring structures.

One of the objects of my invention is to provide a relatively light, durable, elastic and universally yieldable spring supporting structure adapted for upholstering furniture, vehicles, cushions, mattresses, and the like.

Another object of my invention is to produce a structure that will prevent noise, due to contact of adjacent springs and to cheapen the cost of manufacture without decreasing the durability and efficiency of such devices.

Other and further objects of my invention will become readily apparent, to persons skilled in the art, from a consideration of the following description when taken in conjunction with the drawings wherein:

Figure 1 is a plan view of a fragment of my improved structure showing parts of the top cover removed, and some of the springs taken from the lower cover. Fig. 2 is an enlarged transverse section taken on line 2-2 of Fig. 1. Fig. 3 is an enlarged fragment of a modification.

In all of the views the same reference characters are employed to indicate similar parts.

In carrying my invention into effect I provide a fabric top and bottom, and in each I form rows of spring receiving and retaining receptacles, preferably quadrilateral in form, for receiving the terminal rings or convolutions of upholstering springs, preferably of the hour-glass type, at regular spaced apart intervals, said springs being separated by integral laterally projecting parts of the fabric, such as seams, welts, or the like, each spring-receiving space inclosed on all sides by these laterally projecting substantially continuous separating means, being crossed in opposite directions by cords, under which and between the seams the terminal convolutions of the springs are subsequently passed, in the respective covers, thereby physically separating the springs, one from the other, to prevent noise by contact of the springs, and thus providing a most excellent means for retaining the ends of the springs in uniform positions, with respect to each other.

In the drawings, exemplifying one form which my invention may take, 10 is the lower cover, consisting of a relatively coarse fabric, preferably burlap, or the like, to which the end ring 11^a of each of the upholstering springs 11-11 is connected, and 12 is a similar top cover of burlap, to which the other the end rings 11^b of all of the springs 11-11 are in like manner connected, and held spaced apart by both covers without permitting contact at any point, of the respective springs with each other. A series of parallel seams or welts 13-13 are made across the top and bottom 10 and 12, respectively. The seams 13-13 are separated about the same distance apart as the diameter of the largest convolution of the springs 11, so that the springs 11-11 can be comfortably seated between the seams 13-13. Similar, angularly disposed seams 14-14 are made substantially the same distances apart, with respect to each other and are formed in the top and bottom covers at preferably right angles to the seams 13-13, thereby forming quadrilateral recesses with in which to receive the ends of the springs. The seams 13 and 14 project laterally distances from the face of the fabric greater than the thickness of the wires forming the end convolutions of the springs and through the seams cords 15-15 are carried transversely across the seams 13-13 and substantially mid-way between adjoining seams 14-14 in the top and bottom covers and in like manner cords 16-16 are passed transversely across the seams 14-14 and midway between the seams 13-13. The cords 15-15 and 16-16 cross each other in the center of the quadrilateral space encompassed by the seams 13-13 and 14-14. Instead of making seams only, as shown in Figs. 1 and 2, I may provide welts as shown at 13^a in Fig. 3, to make a stronger structure. The fabric at 13^a surrounds a cord 18 forming a welt, to provide stronger and stiffer means for holding the cords 15 in place. After the top and bottom covers, 10 and 12, have been made, in the manner described, the terminal convolutions or rings of the springs 11-11 are slipped in under the crossing cords 15 and 16 and between adjacent seams 13-13 and 14-14 of each of the spaces, the points where the cords cross will then be in

planes of the longitudinal axes of the springs. After the terminal ends of the springs have been passed into the receptacles of one of the covers, say the bottom, 5 the top cover is then laid over the assembled springs and the upper ends of the springs are successively passed between the fabric and the crossing cords, into the receptacles in the top cover as clearly shown in Figs. 10 1 and 2, and the covers 10 and 12 then are sewed together, as at 19 at their marginal edges thus inclosing the springs.

I may or may not use a wire, margin frame 20, around which the top and bottom 15 covers 10 and 12 may be stitched, as shown in Fig. 2. For some constructions the margin frame 20 would be of some advantage and in others it would not be required, but when it is used, it may be secured to the 20 covers at the selvage edges of the assembled springs and the fabric may be made to cover it in the manner shown. When the terminal ends of the springs 11 have been placed under the crossing cords 15 and 16, the 25 rounding seams or welts 13 and 14 will prevent them from moving laterally and the cords will prevent them from moving vertically. They will therefore be retained in the positions in which they have thus been 30 placed with the yieldable fabric, preferable that of the covers, interposed between adjoining springs so that there can be no metallic contact between any two springs and therefore the structure is practically noise- 35 less when in use.

The top and bottom fabrics 10 and 12 are reinforced, by the seams or welts as where the respective seams or welts intersect or cross each other between adjacent springs, 40 without increasing the rigidity of said covers to any appreciable extent.

While I have herein shown a single embodiment of my invention for the purpose of clear disclosure it is evident that changes 45 may be made in the general form and disposition of the parts within the spirit and scope of the appended claims.

Having described my invention, what I 50 claim is:—

1. A structure of the character described

comprising a top and bottom cover, each having parallel, laterally-extending pairs of substantially continuous projections, to provide therebetween receptacles to receive spring ends; a series of open coil springs, 55 having their ends within said receptacles and means for securing the selvage edges of said top and bottom covers together to entirely inclose the springs.

2. A structure of the character described 60 comprising a top and bottom fabric cover, each having integral, laterally-extending substantially continuous projections angularly related by intersecting each other at suitable intervals to provide receptacles to 65 receive the end rings of coil springs; a series of coil springs, having their end rings within said receptacles of the respective top and bottom covers; cords, parallel with and between adjacent projections of a series and 70 passing transversely through the projections of the angularly related series, said cords crossing each other within each spring receiving receptacle and overlying the end rings of the respective springs. 75

3. A structure of the character described comprising a top and bottom fabric cover, each having two series of integral, laterally extending substantially continuous projecting seams, angularly related by intersecting 80 each other at suitable intervals to provide a series of rows of receptacles, to receive the end rings of coil springs; a series of rows of coil springs having their end rings within said receptacles of the respective top and 85 bottom covers; cords parallel with and between adjacent seams of a series and passing transversely through seams of the angularly related series, said cords crossing each other midway over each spring receiving receptacle and overlying the end rings of the 90 respective springs.

In testimony whereof I hereunto set my hand in the presence of two subscribing witnesses.

LOUIS A. SUEKOFF.
